UNITED STATES PATENT OFFICE.

JOHN GELL, OF LONDON, ENGLAND, ASSIGNOR TO THE GELL TELEGRAPHIC APPLIANCES SYNDICATE, LTD., OF LONDON, ENGLAND.

AUTOMATIC TRANSMITTER FOR TELEGRAPHIC SYSTEMS.

1,075,315.

Specification of Letters Patent.

Patented Oct. 7, 1913.

Application filed January 24, 1911, Serial No. 604,487. Renewed February 21, 1913. Serial No. 750,042.

To all whom it may concern:

Be it known that I, JOHN GELL, a citizen of the United States, residing at London, England, have invented certain new and useful Improvements in Automatic Transmitters for Telegraphic Systems, of which the following is a specification.

My present invention relates to the forms of automatic transmitters disclosed by me in Letters Patent of the United States #835,750, November 13, 1906, and 890,042, June 9, 1908, and it consists in the features and combination and arrangement of parts hereinafter described and particularly pointed out in the claims.

In the drawings Figure 1 is a front view of a transmitter embodying my improvement; Fig. 1^a is a detail view; Fig. 2 is a plan view of the instrument; Fig. 3 is a vertical sectional view showing driving mechanism in elevation; Fig. 4 is a perspective view of a double cam or segmental wheel; Fig. 5 is a view of a modified form of main and secondary key action.

As in the patents above referred to, I employ a star feed wheel 1 to engage the feed holes in the tape for feeding it along to present its signal holes to a pair of transmitting pins 2, 2^a. These pins are pivotally mounted respectively on the members 3, 3^a of the main key action, which members are pivoted at 4 to the casing or frame of the apparatus. These members 3, 3^a are operated by a cam or segmental wheel or block 5 of double form, Fig. 4, one member 5 of which operates the front main key member 3 and the other member 5^a of which, set at a quarter turn from that of the first member, operates the rear main key member 3^a. This divided cam 5, 5^a has abrupt shoulders and segmental portions 6 which latter are concentric with the drive shaft of the cam member, and this is true also of the low parts of the cam. The key members are operated to press the transmitting pins upwardly by springs 7, one for each member, only one appearing in Fig. 1, and the high parts of the cam member by acting on the teeth 8 of the key members force the transmitting pins downwardly. The pins pass through the signal holes in the tape when any of these are presented to the pins as they are pressed upwardly, and at such times signal impulses are sent over the line;

should, however, an imperforate part of the tape come over the transmitting pin as the springs exert their force to raise them, the pins will be prevented from rising and no signal will be sent, these features being substantially the same as in the patents mentioned.

The portion of my present improvement now to be described refers particularly to the single and double current system disclosed in my Patent 890,042, referred to, and is as follows: The main key members are combined with hammers 8, 8^a, to have a hammer or striking action on the secondary key member, which is pivotally mounted in a frame bracket at 9, and is made up of arms 9^a, 9^b, and an arm 9^c attached to but insulated from the arms 9^a, 9^b. The hammers are tipped with ivory or other substance for insulation, and instead of carrying these hammers directly on the members 3, 3^a of the main key action, I mount them on active portions of the main key action, consisting of the subsidiary members 3^b, 3^c, of right angular form and pivotally mounted on the frame or casing. The subsidiary portion 3^b of the front main key action is connected with the pivoted member 3 by a link 10, while the subsidiary portion 3^c of the rear key action is connected with the member 3^a by a pin and fork connection 11, Fig. 1^a. The hammers of the main key action strike the arms 9^a, 9^b of the secondary key and oscillate it to make the proper contacts for double current working, the effect in sending the impulses being the same as in the Patent 890,042.

The battery is illustrated at B, having its negative terminal connected with the block 12 and its positive terminal connected with the block 13.

In the position of the parts shown in Fig. 1, the secondary lever is engaging contact 13', and the positive current passes through block 13, contact 13', arm 9^c of secondary key, to the plug E connected with earth, and the negative current goes through block 12, contact 12'', arm 9^b of the secondary key to line through the pivot of said key, and the frame bracket or through connection L to line. When the hammer 8 strikes the arm 9^a of the secondary key, and turns the said key, the positive current will flow through block 13, contact 13'', arm 9^a to line L, and the nega-

tive current will pass through block 12, contact 12', arm 9^c of secondary key to earth.

I provide a jockey roller 14 carried by a spring arm 15 to aid in securing a prompt and firm contact of the secondary key with the contacts of the blocks 12 and 13, and to maintain the connection at the time of reversal, said roller engaging the knife-edge 16 end of the arm 9^a. The spring arm 15 is secured adjustably to a block 16 attached to a plate 17 supported on and insulated from the frame, as shown, adjusting screws 18 passing through slots in the spring arm, so that by adjusting these screws the arm can be tipped slightly on the edge 19 of said block 16. By this the jockey roller may be adjusted toward the end of the arm 9^a to have more or less firm pressure thereon. The spring arm 15 is also adjustable longitudinally in order to position the jockey roller in proper relation to the secondary key. For this purpose I provide a screw 19' passing through a post 20 on the frame, and adapted to be turned by a suitable instrument, so that after loosening the screws 18 and turning the screw 19, the arm 15 will be borne upon and adjusted to any degree of fineness by a partial turn of the screw 19', and for setting the arm back the screw 19' can be first adjusted and the arm 15 forced back against it, and then the screws 18 are tightened to hold the arm securely in its adjusted position.

It will be observed that while I employ the hammer action of the main key members upon the secondary key, the same as in my prior Patent 890,042, I have so organized the parts that the secondary key operates in a vertical plane parallel with or coincident to the plane in which the members of the main key action work, instead of, as in said patent, at right angles thereto, and this plane also, instead of being at right angles to the casing or frame, is parallel to the face of the frame or casing, so that all of the parts of the secondary key action, with its contacts, are located on the outer face of the frame, where they are accessible for adjustment, cleaning, and for rigidity and simplicity in construction. The secondary key action is mounted on the vulcanite block defined by the black line 20', Fig. 1, and this is fixed to the casing or frame which forms a solid backing therefor throughout its extent.

In my present form as in the form shown in my Patent 890,042, the pin carrying portions 3, 3^a, of the main key members are arranged side by side, and in comparatively close proximity, while the active or hammer carrying portions of said main key action, like in said patent, are spread apart to locate the hammers in separated positions to act against the arms of the secondary key action. In effect, therefore, the active hammer

carrying portions 3^b 3^c form extensions or continuations of the pin carrying portions 3, 3^a, in the one case an intermediate connecting link being used, and in the other case the pin and fork connection being employed.

In Fig. 5 I show another form of key action in which the transmitting-pin-carrying portions 3', 3'', of the main key are vertically arranged, and have arms extending at right angles thereto to which the transmitting pins are pivoted, while the active or hammer carrying portions 3^d 3^e of the main key are straight pieces pivoted intermediate of their length, and have their adjacent ends connected by links 10' with the members 3' 3'' respectively, the hammers being carried at their opposite ends. The secondary key is substantially the same as that above described. This form possesses all the advantages of the form first described, and in addition it presents a well balanced organization for uniform working and promptness and firmness of contact.

In both the forms above described the transmitting pins are pressed toward the right by springs against stops, one of each of which is shown at 21 and 22, respectively.

It will be understood that with the cam 5—5^a having the abrupt shoulders and the concentric high and low parts, and with the members of the main key action having the hammers, the secondary key, when subjected to the hammer action, will be promptly operated and not only forced firmly against its contacts by the action of the hammers, but will be held by the springs for a definite period of either contact on or contact off, the concentric low part of the cam permitting this action. The jockey roller aids in securing the prompt and firm contact. By removing the arm 9^c from the secondary key 9^a 9^b, the instrument becomes a single contact transmitter.

Driving mechanism.—The apparatus is driven from any suitable motor through a shaft 23, Figs. 2 and 3, carrying a friction drive disk 24 bearing upon a disk 25 on a shaft 26. This disk 25, through a friction wheel 27, drives another friction disk 28 on the shaft 29, and on this is a gear wheel 30 meshing with a gear 31 mounted on the shaft 32 journaled in the casing, and in a bracket 33, Fig. 2, and upon this shaft the double cam 5, 5^a is mounted. The shaft 32 has fixed thereto a pinion 34 meshing with a gear 35 on the shaft 36 of the star-feed wheel. By this train of gearing the star-feed wheel and the cam 5, 5^a are driven in proper time with each other. The friction disks and wheels are kept in proper driving contact by a spring 37 in a casing 38 fixed to the frame, said spring surrounding the end of the shaft 29 and pressing in a ring or disk 39 loose on said shaft, and bearing upon antifriction balls 40 carried by a ring 41,

said balls, in turn, bearing upon a ring or flange 42, the sleeve 43 of which is pinned at 44 to the shaft 29. For varying the speed of the drive, the driving friction wheel 24 is mounted adjustably on the motor shaft 28, so that by loosening the screw 45 the wheel may be set in different positions toward or from the center of rotation of the disk 25. The transmission friction wheel 27 is mounted in a hanger 46 through which a screw threaded rod 47 passes. This rod or shaft turns in bearings in brackets 48, 49, being held against longitudinal movement by collars 50 pinned on the shaft. By turning the screw shaft the wheel bracket 27 may be adjusted in respect to the centers of rotation of the friction disks 25 and 28 to vary the speed of transmission. A scale 51 is supported on the brackets 48 and 49, and a mark on the hanger 46 will register with the scale marks to secure fineness of adjustment.

It will be understood that the hanger 46 of the intermediate friction wheel 27 permits the proper pressure to be secured between the friction surfaces, this hanger being free to turn about the screw shaft, though no appreciable turning movement takes place in securing adequate pressure for transmission.

I claim:—

1. In apparatus of the class described, a frame, a star feed wheel, transmitting pins,

a cam, a main key action comprising spring pressed pivoted members carrying the pins, subsidiary members pivotally mounted, and connected with the main key members, said subsidiary members having hammers, and a secondary key operated by said hammer, substantially as described.

2. In combination in apparatus of the class described, a star - feed - wheel, transmitting pins, a cam, a main key action comprising spring pressed pivoted members carrying the pins and subsidiary members pivoted intermediate of their length, links connecting the adjacent ends of the subsidiary levers with the pin carrying members, said subsidiary members having hammer portions at their outer or distant ends, and a secondary key operated by said hammer portions substantially as described.

3. In combination the main and secondary key actions, a jockey roller, an arm carrying the same, screws for adjustably holding the arm and a screw for forcing the arm longitudinally to adjust the jockey roller in relation to the secondary key or to form a stop for the adjustment of the arm in the opposite direction, substantially as described.

In testimony whereof, I affix my signature in presence of two witnesses.

JOHN GELL.
